UNITED STATES PATENT OFFICE.

JOHN HENRY THEBERATH, OF VAILSBURG, NEW JERSEY, ASSIGNOR TO
BIPPART, GRISCOM & OSBORN, OF NEWARK, NEW JERSEY.

DESIGN FOR A FRAME FOR BROOCHES OR PENDANTS.

SPECIFICATION forming part of Design No. 34,703, dated July 2, 1901.

Application filed April 25, 1901. Serial No. 57,507. Term of patent 3½ years.

To all whom it may concern:

Be it known that I, JOHN HENRY THEBERATH, a citizen of the United States, residing at Vailsburg, county of Essex, State of New Jersey, have invented a certain new and useful Design for a Frame for a Brooch or Pendant, fully described and represented in the following specification and the accompanying drawings, forming a part of the same.

The present design relates to a frame to which ornaments and jewels may be attached, and which may be employed in a brooch by attaching a pin upon the back and may be applied as a pendant by attaching an eye to suspend the frame.

Figure 1 of the drawings represents the outline of the frame, which constitutes its ornamental feature or quality; and Fig. 2 represents the same in edge view.

The drawings accompanying this specifi-

cation show to any one skilled in the art of making jewelry the ornamental shape of my frame for a brooch or pendant in such a complete manner as to convey a clear understanding of the same and is sufficient to enable such person to use my invention. 25

The design consists in the shape substantially as shown in the drawings.

What I claim as my invention, and desire to secure by Letters Patent, is— 30

The design for a frame for a brooch or pendant, substantially as shown and described.

In testimony whereof I have hereunto set my hand in the presence of two subscribing witnesses.

JOHN HENRY THEBERATH.

Witnesses:

WILLIAM H. ROBERTS,
THOMAS S. CRANE.
